TERMINAL FOR PNEUMATIC-DESPATCH CIRCUITS.

1,158,925.

Specification of Letters Patent.

Patented Nov. 2, 1915.

Application filed September 3, 1912. Serial No. 718,176.

To all whom it may concern:

Be it known that I, CHESTER S. JENNINGS, of Boston, in the county of Suffolk and State of Massachusetts, have invented certain new and useful Improvements in Terminals for Pneumatic-Despatch Circuits, of which the following is a specification.

This invention relates to pneumatic despatch tube apparatus and more particularly to a tube despatch system comprising a plurality of tubes, each of which ultimately exhausts into a common conduit, or receptacle, said tubes being provided with sending terminals or inlets which are so operatively interconnected, that normally but a single one will be open to the atmosphere at a time.

The provision of means, therefore, to the end that when one normally closed inlet is opened, the others which are opened, if there be any such, will automatically close, constitutes one of the objects of the present invention.

Another object is to adapt said means for use in systems of the type in question which are provided with time element mechanism for automatically closing an inlet which has been opened for, let us say, the introduction of a carrier, after the lapse of a substantially determined interval of time, whereby to economize power.

These and other objects of my invention will be hereinafter referred to and the novel elements and combinations of elements whereby they may be attained will be more particularly pointed out in the claims appended hereto.

In the accompanying drawings, which constitute a part hereof, and in which like reference characters designate like parts throughout the several views, I have exemplified a preferred construction, but I am aware that various changes and modifications may be made therein without departing from the spirit of the invention, and hence, desire to be limited only by the scope of said claims.

Referring to the drawings: Figure 1 is a rear elevation of an apparatus embodying my invention, said apparatus in the present instance comprising two terminals disposed side by side. Fig. 2 is a vertical section of said apparatus taken on line II-II of Fig. 1. Fig. 3 is a bottom view of the apparatus shown in Fig. 1. Fig. 4 is a detail partially in section, the section being taken on the line IV-IV of Fig. 1. Fig. 5 is a detail longi-

tudinal section of the rock-shaft bushing and associated parts, hereinafter referred to.

As shown, the transmission tubes, designated 1, are provided with terminals 2, secured thereto in any suitable manner. The lower ends of these terminals are bellied as at 3, to adapt them for the reception of the carrier, and these bell mouths are each provided with a closure, or door, 4. In the present instance, these closures are leather disks secured to plates 5; the latter having ears 6, to which are pivotally connected the door supporting arms 7. The connection between each arm 7, and its plate 5, is preferably a somewhat loose one, and to this end, the ears 6 should have journal openings somewhat larger in diameter than the cotter pins 8, upon which they ride. Each arm 7, is hinged upon a rod 10, which, for convenience of construction, preferably extends transversely past a plurality of the casings 2, at the rear sides thereof; being mounted in ears 11, which project downwardly and rearwardly from said casings.

Straddling the rear ends of the arms 7, and also pivotally mounted upon the rod 10, are weighted bifurcated arms 12. These preferably consist of sheet metal channels, which open downwardly; the web 12' of each channel being apertured as at 13, for the reception of a yoke 14, hereinafter referred to. Within each channel are secured metal blocks 15-16, which constitute weights which tend to swing the arm 12, to which they are attached, downwardly into a position where its weight 15, may engage a lug 17, on the corresponding arm 7, so as to elevate the latter together with its door, and thereby cover the bell mouth 3. The yoke 14 aforesaid, is pivoted to the sides of the channeled arm 12, as at 18, and the horizontal portion 19 thereof is apertured to loosely receive a plunger rod 20, which depends from a piston 21, being connected thereto by a pin 22, or the like. This piston may comprise a center piece or head 23, through which pin 22 extends and around which is a packing ring 24. The upper end of the piston head is flanged and washers 25 may be provided upon the respective sides of the packing ring to prevent lost motion. Piston 21 rides in a cylinder 26 which is mounted in a clamping bracket or split collar 27, one of which projects rearwardly from each terminal 2. The upper end of the cylinder 26

100
95
105
110

may be threaded into a cap 28, which latter is also attached to the tube 1, by a split collar 29. Each cap 28 is also provided with means for connecting the hollow interior thereof with a vacuum main 30. In the present instance, this means comprises a semi-circular bracket 31, which is flanged at its extremities to fit a correspondingly shaped band 32; the cap 28 being apertured at 33, and the main or pipe 30 held between the parts 31 and 32, being apertured at 34, so that the air within the space 35, in the lower part of the cap may pass out thence directly into said main; the speed of its movement, however, being determined by the position of the valve 36.

The cylinder 26 opens into a chamber 37 in the upper portion of the cap 28; said chamber being separated from the space 35 by a septum in which the upper extremity of the cylinder 26 is screwed. In this septum, to one side of said cylinder, is a port 38 which places the chamber 37 in connection with space 35, when the valve 39 is raised. This valve is mounted upon a stem or rod 40, the upper extremity of which extends downwardly through the lower wall 42 of the cap, through a tube 43, which is secured in said wall, and through a portion of the top of the terminal 2, into the interior of the latter. Loosely pivoted within this terminal is a light vane 44, of aluminum or the like, which, when the door, or cover 4 is opened, is drawn upwardly at an angle by the current of air flowing into the tube. When the vane 44 is in the position in which it is shown in Fig. 2, its weight, while light, is nevertheless, sufficient, by reason of the leverage provided therefor, to maintain the small bell crank 45 in the position indicated, while when the vane is lifted by the inrush of air, the stem 40, which rests upon the short arm 46 of the bell crank, rotates the latter counter-clockwise until the valve 39 has seated itself and thereby closed port 38. The vane 44 is of course free to swing upwardly out of operative engagement with the bell crank 45; being mounted for oscillatory movement independent of the latter, save when the shouldered part 45' of the bell crank is engaged by the vane. Undue rotation of the bell crank 45 is prevented by the engaging of the under side of the short arm 46 with a ledge 47 provided within the terminal. The depending arm of the bell crank is curved to adapt it for engagement with the side of a carrier which may be inserted into the terminal, while the vane is in like manner so shaped that it may substantially fill the space, one wall of which has been designated 48, provided therefor in the inner wall of the terminal and guide the carrier past said space. The vane 44 may have a buffer button 49 to limit its upward movement and obviate unnecessary

noise, said button engaging the terminal wall at 50.

A valve 51, which may be closely adjusted, normally admits air slowly to the chamber 37, but a button 52 of rubber, or the like, carried by the center piece 23 may cut off part of this admission of air when the piston is in its uppermost position, if desired. This button also acts as a buffer for the piston upon its upward stroke. 75

The lower end of the rod 20 is enlarged or headed to adapt it to lift the yoke and thereby the weighted arms 12, when nearing the upper end of the stroke of said rod.

The lower end of the cylinder 26 may be closed by a head 53, through the center of which the rod 20 extends and to the underside of which is pivoted a latch 54 which normally engages the free end of the arm 12, as shown in Fig. 2, when said arm has been elevated by the piston 21 in the manner hereinafter described. A portion 54' of the latch 54 is extended up through head 53 into the cylinder and the lower end of the center piece 23 is somewhat pointed to adapt it to press portion 54' laterally and thereby lift the latch proper when the piston reaches substantially the limit of its downward travel. 90

An extending bushing 55 may be secured in lugs 56 which constitute parts of the respective terminal and a square rock shaft 57 is disposed in this bushing; the extremities of the rock shaft being turned and journaled in collars or sockets 58 mounted upon the respective ends of the bushing; cotter pins 59, or the like, in the ends of shaft 57 serving to retain the latter together with collars 59 in place. The sleeve or bushing 55 is laterally slotted at intervals as at 60 and latches or catches 61, preferably of sheet metal, are inserted into these slots and are fixedly mounted upon the square shaft 57 so that all of said catches rise and fall together, the slots 60 being of sufficient length, as shown in Fig. 4, to allow of movement to disengage the latches from the pins 62 with which they may be in engagement. Each of these pins projects laterally from a weighted arm 63 of a bell crank, broadly designated 64, as best shown in Fig. 3. These bell cranks are rotatably mounted upon the rod 10, previously referred to, so that their respective shorter arms 65, (see Figs. 1 and 4), when the weighted or longer arms are not latched up, tend to drive the closures 4 up toward the mouths of the respective terminals 3; each of said shorter arms having a lateral extension 66, which is adapted for engagement with the arm 7 of the corresponding closure. Each latch 61 is shaped, as shown in Fig. 4, so that when a pin 62 is driven upwardly thereagainst, said latch will raise and will thereby rotate the rock shaft and raise all the 110

115

120

125

130

5 latches in this group of the same; the particular latch engaged by the pin thereafter hooking said pin but the remaining weighted arms 63, in the meantime, having pulled all other pins 62 out of their latching positions so as to leave but one such arm latched up.

10 The operation of the device is as follows: Normally all tubes 1 are closed by the covers 4 and the pistons 21 are all in their uppermost positions. Assuming now, that one closure 4 is pulled down by the hand of the operator pressing downwardly upon the extremity of an arm or lever 7. Immediately 15 vane 44 is raised by the inrush of the air into tube 1, due to the partial vacuum present in the latter, and the valve 39 drops by gravity; closing the port 38. Sufficient air seeps in through the bleed 20 hole controlled by the adjusting valve 51 to equalize the pressure upon the respective sides of the piston and the latter slowly descends. If no carrier be inserted into the 25 terminal the piston will fall until the rounded lower end of the piston head 23 rocks the latch 54 and thereby releases the weighted arm 12 which falls and closes the door 4. Once the latter has been swung into engagement with the bell mouth, atmospheric 30 pressure will retain it there. The vane 44 is then free to fall and, in turn, lifts the valve 39 and permits the air in chamber 37 to exhaust out through the space 35, past the adjusting valve 36 into the vacuum main 35 30. Atmospheric pressure promptly elevates the piston and the parts again occupy their former position. The time taken by the piston to descend determines the time that air shall be admitted freely to a given 40 tube 1, and this portion of the apparatus, hence, constitutes a time element means. If a carrier is inserted into the tube 1, before the automatic re-closure of the same, it will 45 press the depending arm of the bell crank 45 laterally, in passing said arm, which momentarily re-elevates the stem 40 and opens the port 38. The air which, in the interim, has entered chamber 37 rushes out and the piston is again elevated. The insertion 50 of a carrier forces the door 4 open to such an extent as to elevate its weighted closing arm 63 to its latching position whereupon the latch 61 engages the pin carried by said arm so that nothing tends to 55 re-close the door until the requisite time elapses before the release of the arm 12, as above described. If, while one door or closure 60 of a given set or group of inlets is still open, one opens a second door and inserts a second carrier therethrough into a corresponding tube, this action results in rocking the shaft 57 and unlatches the weighted bell crank 64 which corresponds to the first 65 opened door, and thereby promptly closes the latter. Thus, but one door in a group

may normally be fully opened at any one time and all will normally be automatically closed after the lapse of sufficient time to impel a carrier through any given tube. It is to be understood, however, that the several time element mechanisms may be differently adjusted to meet the demands of the system.

70 In referring to the inlets as being disposed in a group I do not wish it to be inferred that the plurality of terminals or inlets are necessarily side by side or closely adjacent, since various dispositions of these parts and various means for interconnecting them will suggest themselves to those skilled in the art.

75 One other feature remains to be considered. Within the cap 28 is a gripping lever 68 pivoted in front of the rod 40, as at 69. Rod 40 extends up through an aperture or slot in this lever and the wall of said slot, nearest the pivot 69, is adapted to frictionally grip said rod when the free end of the lever is permitted to drop. The piston head 23 lifts the lever 68 whenever the piston is in its uppermost, or substantially its uppermost position, which frees rod 40 from the action of said lever and permits it to drop and close the port 38 whenever the vane 44 is lifted in the manner previously 85 described. Owing to the gripping action exerted by the lever 68, however, whenever the piston is in other than its uppermost position, the rod 40 when even but momentarily raised, either by the fall of the vane 90 44 or by the introduction of the carrier into the terminal, will remain raised, leaving the port 38 uncovered until the piston has moved upwardly to the limit of its travel. This insures that even the last one of a plurality 95 of carriers introduced into a given group of terminals shall have its full quota of time for transmission.

100 It will be evident, of course, that the rod 40 is not held against upward movement, by 110 the lever 68, but only against downward movement under the conditions described.

110 In general, it will be observed that I have provided a plurality of substantially independently acting means for closing each closure; one of these means including a given weight 63 and operating when one closure is opened to unlatch said given weight 63 of the previously opened gate and to allow said weight to thereupon swing said gate to its closed position. The other of said means is the arm 12 with its weights 15 and 16, which when said arm is released by the descent of piston 24, effects the closure 120 of the corresponding gate; the arm 12 of course being again latched up as soon as the piston has risen to its uppermost position.

125 In a system of the character to which the present invention more particularly relates it is important that one of the closures be 130

free to open as soon as the vacuum is broken in the transmission line or lines, as for example, by the opening of a gate for the insertion of the carrier at a distant station, in 5 a manner common in the art; and since there will always be one weight 63 latched up it is evident that this gate, obviously depending upon which one was last operated at the station where the group of inlets is 10 located, will be the one to drop open as soon as the pressure of the air upon the respective sides of said gate becomes equalized. Hence, it may be briefly stated that one of the principal objects of the present invention 15 has been to provide means for applying force to move any closure which may previously have been opened, to its closed position, as soon as another closure is opened; the force applying means for this last 20 opened closure remaining thereafter substantially inoperative until some other closure has been opened; while a second set of force applying means or elements are controlled by time element mechanism so that after the 25 lapse of a determined interval of time, subsequent to the opening of the last opened closure, all closures will occupy their closed positions; and the mechanism further so operating as to then render substantially in- 30 operative the force applying means which is controlled by the time element mechanism.

Claims:

1. A pneumatic despatch tube apparatus having a group of inlets, each of which is 35 provided with a closure, each of said closures being movable into its open position regardless of the disposition of another closure in the group, mechanism for automatically closing one closure in said group when another is opened in excess of a determined amount, and mechanism for causing said last opened closure to move to its closed position thereafter.

2. A pneumatic despatch tube apparatus 45 having a group of inlets each of which is provided with a closure, mechanism for automatically closing one closure in said group when another closure is opened in excess of a determined amount, and means for normally closing said last opened closure thereafter.

3. A pneumatic despatch tube apparatus 55 having a group of inlets each of which is provided with a closure, mechanism for automatically closing one closure in said group when a second closure is opened in excess of a determined amount, and pneumatically controlled means for automatically closing said second closure within a determined interval of time after the opening of said second closure.

4. A pneumatic despatch tube apparatus 65 having a group of inlets each of which is provided with a closure, mechanism for automatically closing one closure in said group

when another closure is opened in excess of a determined amount, and time element means for normally closing said last mentioned closure thereafter.

5. A pneumatic despatch tube apparatus 70 having a group of inlets each of which is provided with a normally closed closure, means for moving said closures from their open toward their closed positions, means for restraining said moving means from closing a given closure after the latter has 75 been intentionally opened in excess of a determined amount, and means for rendering inoperative said restraining means when another of said closures is opened a determined 80 amount.

6. A pneumatic despatch tube apparatus having a group of inlets each of which is provided with a closure, individual means 85 for moving said closures from their open toward their closed positions, means for restraining said moving means from closing a given closure after the latter has been intentionally opened in excess of a determined amount, means for rendering inoperative 90 said restraining means when another of said closures is opened a determined amount, and means for normally closing said given closure in any case after the lapse of a substantially determined period of time. 95

7. A pneumatic despatch tube apparatus having a group of inlets each of which is provided with a normally closed closure, means for moving said closures from their open toward their closed positions, a latch 100 for restraining said moving means from closing a given closure after the latter has been intentionally opened in excess of a determined amount, and means, including a second latch and connections between said 105 latches, for rendering inoperative said restraining latch when another of said closures is opened a determined amount.

8. A pneumatic despatch tube apparatus having a group of inlets each of which is 110 provided with a closure, means for moving said closures from their open toward their closed positions, a latch for restraining said moving means from closing a given closure after the latter has been intentionally opened 115 in excess of a determined amount, means for rendering inoperative said restraining latch when another of said closures is opened a determined amount, and means for thereafter closing said last mentioned closure. 120

9. A pneumatic despatch tube apparatus having a group of inlets each of which is provided with a closure, means for moving said closures from their open toward their closed positions, a latch for restraining said 125 moving means from closing a given closure after the latter has been intentionally opened in excess of a determined amount, means, including a second latch and rigid connections between said latches, for render- 130

ing inoperative said restraining latch when another of said closures is opened a determined amount, and auxiliary means for closing said last opened closure.

5 10. A pneumatic despatch tube apparatus having a group of inlets each of which is provided with a closure, mechanism for automatically closing one closure in said group when a second closure is opened in excess of a determined amount, said mechanism including an operating arm for each of said closures, each of said arms being movable independently of its closure when the latter is in its closed position, means for automatically closing both of said closures within a determined interval of time after the opening of said second closure, said means including operating arms independent of those first mentioned, and a common pivotal shaft for all of said arms.

20 11. A pneumatic despatch tube apparatus having a group of inlets each of which is provided with a closure, and a plurality of substantially independent means for moving each closure of each of said inlets to its operative position, and one of said means for said given closure having an operative connection with one of said means of another closure, whereby when said other closure is opened said given closure is closed.

25 12. A pneumatic despatch tube apparatus having a group of inlets each of which is provided with a closure, a plurality of weights for actuating each closure, means for holding said weights inoperative, manually operated means for releasing one weight of a given closure, and automatic means for releasing another weight of said closure, each of said independent means for a given closure being adapted to close the latter while leaving another of said independent means for said closure undisturbed, within a determined period of time after the opening of said closure, if said manually operated means be not actuated before the expiration of said period, said manually operated means of said closure being operatively connected to a corresponding means for another of the closures in said group.

30 13. A pneumatic despatch tube apparatus having a group of inlets, closures for said inlets having provisions for causing movement thereof into their closed positions, means for maintaining open a closure of a given inlet in said group, manually controlled means for causing said last mentioned closure to move to its closed position upon the opening of another inlet, and automatic means for causing said closure to move to its closed position if it be not manually caused to be closed within a determined period of time.

35 14. A pneumatic despatch tube apparatus having a group of inlets, closures for said inlets, means for holding open said closures,

and a plurality of independently acting means for causing the movement of each of said closures to its operative position, one of said means having provisions for releasing a closure which has been operatively disposed by said last mentioned means from further subjection to such means until said closure has again been opened.

40 15. A pneumatic despatch tube apparatus having a group of inlets each in communication with a tube in which there is normally a partial vacuum, each of said closures normally adapted to be maintained closed by atmospheric pressure when moved to its closed position, said closures having a tendency of themselves to open but having provisions normally tending to close them, means for restraining said provisions whereby to maintain any one of said closures in its open position, means for releasing said provisions of said last mentioned closure when another closure in said group is opened, means for normally ultimately closing all of said closures which may still be open, and co-acting means for rendering said last mentioned means inoperative thereafter, whereby to thereafter maintain at least one of said closures in its closed position by said atmospheric pressure substantially alone.

45 16. A pneumatic despatch tube apparatus having a group of inlets each in communication with a tube in which there is normally a partial vacuum, each of said closures normally adapted to be maintained closed by atmospheric pressure when moved to its closed position, means for closing said closures, means for restraining the closing means of any one of said closures, means for releasing said closing means of said one when another closure in said group is opened, and time-element means for normally ultimately closing all of said closures which may still be open after the lapse of a period determined by said time element means and running from the opening of the last opened one of said closures.

50 17. A pneumatic despatch tube apparatus having a group of inlets each in communication with a tube in which there is normally a partial vacuum, each of said closures normally adapted to be maintained closed by atmospheric pressure when moved to its closed position, means for closing said closures, means for restraining the closing means of any one of said closures, means for releasing said closing means of said one when another closure in said group is opened, and time-element means for normally ultimately closing all of said closures which may still be open and thereafter leaving said atmospheric pressure substantially alone to maintain one of said closures in its closed position.

55 18. A pneumatic despatch tube apparatus

- having a group of inlets, closures for said inlets, means for applying force to close an open one of said closures when another closure in said group is opened, means for applying force to close said other closure, thereafter, and means for rendering one of said force applying means substantially inoperative after the closure closed thereby has been moved to its closed position.
- 10 19. A pneumatic despatch tube apparatus having a group of inlets, closures for said inlets, means for applying force to close an open one of said closures when another clos-

ure in said group is opened, means for applying force to close said other closure 15 thereafter, and means for rendering the latter of said force applying means substantially inoperative after the closure closed thereby has been moved to its closed position. 20

In testimony whereof I have affixed my signature, in the presence of two witnesses.

CHESTER S. JENNINGS.
